(57) **CLAIM**

The ornamental design for a tyre, as shown and described.

DESCRIPTION

FIG. 1 is a first perspective view of a tyre in accordance with our new design;

FIG. 2 is a front elevation view thereof;

FIG. 3 is a left side elevation view thereof; and,

FIG. 4 is a right side elevation view thereof.

The broken line showing of text and an icon in FIG. 2 is included for the purpose of illustrating portions of the tyre and forms no part of the claimed design.

1 Claim, 4 Drawing Sheets

FIG. 1

FIG. 2

FIG. 3

FIG. 4
